Application June 9, 1933, Serial No. 675,070

72 Claims. (Cl. 123—51)

This invention relates to power development and has for an object the provision of certain improvements in the construction and operation of power units. The invention relates particularly to engines of the internal combustion type and contemplates the provision of engines of simple construction capable of highly efficient operation with a wide variety of fluid fuels. The invention also contemplates the provision of an improved fuel induction system for internal combustion engines. The invention further contemplates the provision of an improved method for lubricating step pistons. A further object of the invention is to provide an improved engine of the type in which opposed pistons act in each cylinder.

While many of the features of the invention are of broad application, all are particularly suitable for use in internal combustion engines of the type in which opposed pistons act in each cylinder. Therefore, the novel features of the invention will be discussed and described hereinafter with reference to their employment in engines of the type in which opposed pistons act in each cylinder. It is to be understood that the following discussion and description are provided for purposes of illustration and not for purposes of limitation, and the appended claims are to be accorded all reasonable interpretations not inconsistent with the terminology employed therein.

Engines of the general class in which opposed pistons act in each cylinder, possess certain obvious features of advantage over engines in which only a single piston acts in each cylinder. Among these advantages are the reduction of frame stresses; reduction of main crank shaft bearing loads; more favorable dynamic characteristics, including the possibility of perfect balancing of both reciprocating and rotating parts; desirable shape of combustion chambers; reduction in water-jacketed area; improved scavenging of two-stroke-cycle engines, because scavenging air and exhaust ports can encircle and be located at opposite ends of the cylinder.

It has been proposed to employ opposed pistons in each cylinder of engines of the two following types:

(1) Single cylinder engines or engines of the type in which several cylinders are all disposed on one side of a crank shaft serving them all with their axes at right angles to the axis of the crank shaft; and

(2) Engines of the type in which cylinders are disposed in axial alignment on opposite sides of a crank shaft with two connecting rods extending

to a wrist pin on one side of the crank shaft and controlling the movement of a pair of outer pistons, and one connecting rod extending to a wrist pin on the opposite side of the crank shaft and controlling the movement of a pair of inner pistons. 5

In spite of the many advantages which may be obtained through the use of the opposed-piston principle in engine design and operation, opposed piston engines of the type proposed heretofore are not widely used because of certain inherent disadvantages which limit their application and make them compare unfavorably with engines having but a single piston in each cylinder. Thus, single cylinder engines and engines of the type in which several cylinders are all disposed on one side of a crank shaft can not be perfectly balanced, because the connecting rods serving the outer piston of each cylinder will not at all times form the same angle, with respect to the cylinder axis, as the connecting rods serving the inner piston of the same cylinder, and thus the inner and outer pistons will not move at all times with equal and opposite accelerations and the inertia forces will not be balanced. The magnitude of these unbalanced forces is increased, as compared with single-piston engines of the same cylinder arrangement, because of the greater weight of the reciprocating parts of the opposed piston engine, which in turn is due to the additional elements needed to connect the outer piston with the crank shaft. These increased reciprocating weights have the further disadvantage of producing increased inertia pressures and consequently increased loads on wrist pin and crank pin bearings. 25 30 35

Opposed piston engines of the type in which cylinders are disposed in axial alignment on opposite sides of a crank shaft can be perfectly balanced and can be so constructed that the bearing loads due to inertia of the reciprocating parts are diminished by opposing gas pressures acting on the pistons. The engines of this type proposed heretofore have been provided with sleeve pistons or reciprocating power cylinders which have their outer ends closed to serve as the outer pistons of each cylinder, while their inner ends are open to receive the inner piston of each cylinder. 40 45

The use of these reciprocating cylinders imposes several difficulties and disadvantages of such seriousness that they have not been adopted for commercial use. They must be lubricated inside and outside; they double the rubbing velocity of the inner piston, which greatly reduces 50 55

the life of the engine; they must be cooled themselves and must also serve to cool the inner piston, so that the heat extraction from the inner piston must take place through two oil films and through both the wall of the reciprocating cylinder and the wall of the outer stationary cylinder. The reciprocating cylinder is itself exposed to the hot gases of combustion, and it is further burdened with conducting heat from its outer end.

Heretofore, designers of engines having opposed cylinders and opposed pistons in each cylinder have encountered a further difficulty in providing straight-line connecting elements between either the inner pair or the outer pair of pistons of opposite cylinders. In designing such engines they have usually employed two- or three-throw crank shafts, and they have resorted to large bores with relatively very short strokes, so that the connecting means could clear the crank shaft and connecting rods; or else they have arched or curved the connecting elements of at least one pair of pistons for the same purpose. These connecting elements are subjected to heavy loads and, if they are not straight, bending moments of great magnitude occur in them, and repeated flexure soon destroys them. Increasing the bore and reducing the stroke, for any given piston displacement, increases the bearing pressures as the square of the increase in bore diameter, so that larger crank pins and connecting rods are required and it becomes practically impossible to construct a serviceable engine with straight-line connecting elements between the inner pistons, and in which said elements are spaced far enough apart to clear the crank pins, arms and connecting rods of a three-throw crank shaft operating between them.

If a two-throw crank shaft is used in such an engine, it is obviously impossible to avoid either bending the connecting rods or off-setting them with respect to the forces acting through them in line with the cylinder axis. Curving the connecting rods (I now refer to connecting rods between pistons and crank shafts) results in producing bending moments in them, with consequent flexure; and the alternative of off-setting the rods with respect to the axis of the cylinders, causes tilting of the pistons within the cylinders and consequent rapid wear of both pistons and cylinders. Three-throw crank shafts, in such engines, must either incur the objections just stated for a two-throw shaft, or else the center throw must act so that the center of its connecting rod is in the same plane as the axis of the cylinders, and the other two throws must be equally spaced on opposite sides of the said plane. Any of these constructions encounter the aforementioned impossibility of providing straight-line connecting elements between the inner pistons in combination with feasible relations between bore, stroke and bearing areas.

I have developed an opposed-piston type of engine which possesses all of the aforementioned 65 advantageous features of engines employing this principle and few, if any, of the undesirable features of the heretofore proposed engines of the opposed-piston type. The engine of my invention comprises spaced, axially aligned cylinders, 70 and two pistons mounted for reciprocating movement within the opposite end portions of each cylinder.

The preferred form of engine of my invention comprises two axially aligned cylinders disposed 75 on opposite sides of a crank shaft. Two pistons

are mounted for reciprocating movement in each cylinder, one within the inner end portion of the cylinder and one within the outer end portion of the cylinder. The pistons in the adjacent end portions of the cylinders (the inner pistons) 5 are rigidly connected to each other, and the pistons in the opposite end portions of the cylinders (the outer pistons) are rigidly connected together. The inner pistons and outer pistons are units extending between the cylinders and mounted for reciprocating movement in opposite directions.

I have overcome the disadvantages resulting from failure to provide connecting straight-line elements in engines of the type proposed heretofore by employing a form of crank shaft which provides two throws for operating a pair of outer pistons, and two throws for operating a pair of inner pistons; and which provides a clearance space, between the two throws which serve the 20 inner pistons, through which the straight-line connecting elements between the inner pistons can pass. This arrangement contributes to a more favorable bore-stroke relationship; avoids bending moments in either connecting rods or 25 connecting elements between the inner pistons; avoids non-concentric loading of pistons; and reduces weight and bearing loads.

In the preferred form of engine of my invention, I employ step or differential pistons which 30 serve the dual purpose of power pistons and pumping pistons for providing scavenging air, and I provide simple and efficient means for lubricating such pistons. Efforts to lubricate step pistons by means of oil-splash or oil-mist produced in the engine crank cases have been largely unsuccessful heretofore. If the step piston is used with the large diameter toward the crank case, it is difficult to get sufficient oil past the 40 large end to lubricate the smaller portion which 40 serves as a power piston. Or, if this should be accomplished, it must be done by allowing oil to get past the large end of the piston and into the scavenging pump chamber, whereupon, of course, most of it is blown by the scavenging air 45 into the power cylinder and burned or wasted. Engines heretofore designed with a step piston in the outer end of a cylinder have never, so far as I am aware, provided means of conveying oil-laden crank case atmosphere to said piston in a 50 manner to provide sufficient lubrication for its rubbing surfaces, and without mixing said oil with the scavenging air, and with provision of means for returning all excess oil to the crank case. I accomplish this by circulating high 55 velocity currents of atmosphere between the crank case and the step pistons in the outer ends of the cylinders. These currents of air, carrying atomized oil, do not reach the chamber in which scavenging air is compressed, so that no oil is 60 lost by being mixed with the scavenging air. It would be possible to obtain fair lubricating oil economy in such an engine, if the step pistons were lubricated by direct forced-feed of oil to their rubbing surfaces in measured volumes per stroke, but this would require additional apparatus at increased cost, and would not be as simple, positive or economical as my entirely automatic system.

The apparatus of my invention for supplying 70 fuel to the engine cylinders may include a pre-combustion chamber communicating with the interior of the combustion chamber of each cylinder and provided with ignition means. The pre-combustion chambers are connected by 75

means of suitable conduits to a source of supply of fuel. In the preferred form of apparatus, a vaporizing or atomizing device is included in the fuel supply line. The arrangement is such that hot gases may flow from the combustion chambers through the vaporizing or atomizing device and provide the energy required to effect vaporization or atomization and injection of the fuel. By employing pre-combustion chambers having restricted ports leading to the cylinders and by employing combustion gases for injecting the fuel into the pre-combustion chambers, I can employ high compression pressures without causing pre-ignition and without causing detonation.

When oil is to be employed, I prefer to provide atomizers having small cylindrical atomizing chambers and substantially parallel tangential inlet and outlet passages for gas under pressure on opposite sides of the chamber. This arrangement of passages causes entering liquid to be guided in a circular path of travel during the course of which it must pass over the lip defining the inner edge of the outlet passage.

The invention will be better understood from a consideration of the following description in conjunction with the accompanying drawings in which is shown a preferred embodiment of the complete apparatus of my invention, and,

in which

Fig. 1 is a sectional elevation, taken substantially along the line 1—1 of Fig. 2, of an engine of my invention;

Fig. 12 is a plan view of the pre-combustion chamber illustrated in Fig. 11;

Fig. 13 is a section of a single-chamber atomizer or vaporizer of the invention, taken substantially along line 13—13 of Fig. 14;

Fig. 14 is a section taken substantially along line 14—14 of Fig. 13;

Fig. 15 is a section taken substantially along the line 15—15 of Fig. 14;

Fig. 16 is a section of a duplex or double-chamber atomizer or vaporizer of the invention, taken substantially along the line 16—16 of Fig. 17;

Fig. 17 is a section taken substantially along the line 17—17 of Fig. 16;

Fig. 18 is a diagrammatic illustration similar to that shown in Fig. 9, but showing a modified fuel system; and

Fig. 19 is a sectional view of the atomizer in-

cluded in the modified fuel system shown in Fig. 18.

The engine illustrated in the drawings is a two-cycle internal combustion engine comprising two axially aligned cylinders 20 and 21 disposed on opposite sides of a four-throw crank shaft 22 and having opposed pistons 23 and 24 and 25 and 26 mounted therein. The crank shaft is bored for forced feed lubrication, and suitable means (not shown) are provided for accomplishing forced feed lubrication. The outer pistons 23 and 26 are step pistons, the outer end portions of which are enlarged. The large-diameter end portions of the step pistons 23 and 26 are enclosed in cylindrical casings 27 and 30 which communicate with the outer end portions of the cylinders 20 and 21 and which serve as scavenging pump cylinders, the large-diameter end portions of the outer pistons serving as pistons for the scavenging pumps.

The outer pistons 23 and 26 are rigidly connected together and to a cross-head 31 by means of straight-line tie rods 32. The outer pistons 23 and 26 are spaced apart and maintained in fixed positions relatively to each other and to the cross-head 31 by means of tubes 33 and 34 which surround or encase the tie rods and extend between and engage the pistons and the cross-head.

The cross-head 31 is in the form of a ring, and it has an external diameter greater than the internal diameter of the cylinder 21. The outer surface of the cross-head is smooth, and the cross-head is so mounted that its outer surface engages the smooth inner surface of a cylindrical casing 35 which communicates with the inner portion of the cylinder 21. A similar cylindrical casing 38 is associated with the inner portion of the cylinder 20.

The inner pistons 24 and 25 are rigidly connected together by means of straight-line tie rods 36 which are shown as formed integrally with the pistons but which may be of any suitable construction.

A wrist pin 37 is mounted on the annular cross-head 31 with its axis extending parallel with the axis of the crank shaft 22 and at right angles to the common axis of the cylinders 20 and 21. Two similar connecting rods 40 and 41 connect the wrist pin 37 with two outer, spaced but axially aligned crank pins of the crank shaft 22.

A wrist pin 42 is mounted on the piston 24 with its axis extending parallel with the axis of the crank shaft 22 and at right angles to the common axis of the cylinders 20 and 21. Two similar connecting rods 43 and 44 connect the wrist pin 42 with two inner, spaced but axially aligned crank pins of the crank shaft 22.

The inner crank pins and outer crank pins are spaced apart angularly but all are in the same circle. The axes of the wrist pins 37 and 42 and the crank shaft 22 and the common axis of the cylinders 20 and 21 all lie in the same horizontal plane.

The crank shaft 22 is so constructed as to provide a clearance space between two of its cheeks which permits the passage in a straight line of the tie rods 36 by means of which the inner pistons 24 and 25 are rigidly connected together. This clearance space permits the tie rods 36 to be of adequate cross section to carry the stresses to which they are subjected and to be straight columns and thus free from bending moments due to forces acting directly on them in line with the axes of the cylinders.

The inner ends of the similar casings 35 and 38 associated with the inner ends of the cylinders 20 and 21 are spaced horizontally from each other and from the crank shaft 22. A central casing section 45 forms a supporting structure for the engine and provides support for bearings 46 and 47 in which the opposite end portions of the crank shaft are supported for rotation. The central casing section and the similar casings 35 and 38 cooperate to provide a crank case which may be sealed to prevent dust from entering. A flywheel 50 is mounted on one end portion of the crank shaft.

The cylinders 20 and 21 are provided with exhaust ports 51 and 52 adjacent their inner ends which communicate with exhaust manifolds 53 and 54 and with inlet or transfer ports 55 and 56 adjacent their outer ends. The scavenging pump cylinders 27 and 30 are enclosed by rectangular casings 57 and 60, the outer closed ends of which form cylinder heads for the scavenging pump cylinders. The inlet ports 55 and 56 communicate with the interiors of the scavenging pump cylinders through the triangular passages 61 and 62 formed between the rectangular casings 57 and 60 and the scavenging pump cylinders 27 and 30 on one side, which triangular passages communicate in turn with annular passages 58 and 59. On the other side, ports 63 and 64 provide means of communication between the atmosphere and the interior of the scavenging pump cylinder through intake manifolds 65 and 66.

The cylinders 20 and 21 are provided with cooling water jackets 67 and 70. The water jacket 67 surrounding the cylinder 20 comprises three annular chambers 71, 72 and 73, chambers 71 and 72 being separated by the walls defining the annular air inlet passage 58, and chambers 72 and 73 being separated by the walls defining the substantially annular exhaust passage 74. The three chambers comprising the water jacket surrounding the cylinder 20 are connected by means of suitable conduits which provide for the circulation of water therebetween. Thus, (Figs. 3 and 4) conduits or passages 75 at the sides and conduits or passages 76 at the top and bottom provide means of communication between chambers 71 and 72. Similarly, a relatively large upper passage 77 and a relatively small lower passage 80 provide means of communication between chambers 72 and 73.

The water jacket 70 surrounding the cylinder 21 comprises three annular chambers 81, 82 and 83 corresponding to the chambers 71, 72 and 73 comprising the water jacket 67. The chambers 81 and 82 are separated by the walls defining the annular air inlet passage 59, and chambers 82 and 83 are separated by the walls defining a substantially annular exhaust passage 84 similar to the exhaust passage 74 associated with the cylinder 20. Passages or conduits 85 and 86 similar to the passages 75 and 76 provide means of communication between the chambers 81 and 82 and passages or conduits 87 and 90 similar to the passages 77 and 80 provide means of communication between the chambers 82 and 83.

Suitable means (not shown), which may include a pump and a radiator, are provided for circulating the water through the water jackets.

Each of cylinders 20 and 21 has associated therewith conduits or passages through which oil laden atmosphere may pass from the crank case to the cylinder in which the large diameter portion of the step piston associated therewith is confined. Thus, conduits 91 are mounted within and

at the sides of the water jacket 67 surrounding the cylinder 20, and conduits 92 are mounted within and at the top and bottom of the water jacket 67. The conduits 91 and 92 are open at their ends, and they extend from the cylindrical casing 38 associated with the inner end portion of the cylinder 20 to the cylindrical casing 27 in which the large-diameter portion of the step piston 23 is confined. The upper conduits serve the double function of casings for the tie rods 32 and conduits for the flow of oil-laden atmosphere from the crank case to the step pistons.

The water jacket 70 is provided with conduits 93 and 94 similar in construction and function to the conduits 91 and 92, respectively. The conduits 93 and 94 are open at their ends, and they extend from the cylindrical casing 35 associated with the inner end portion of the cylinder 20 to the cylindrical casing 30 in which the large-diameter portion of the step piston 26 is confined.

Any suitable apparatus may be provided for supplying fuel to the engine hereinbefore described.

The apparatus shown in the drawings for providing fuel to the engine comprises two similar pre-combustion chambers 95 and 96 which communicate with the interiors of the cylinders 20 and 21, respectively, and a fuel atomizer or vaporizer 97 (Figs. 7 and 9). The atomizer or vaporizer 97 is connected to both pre-combustion chambers by means of conduits 100 and 101.

An additional atomizer 102 is shown suitably connected directly to the power cylinders 20 and 21 by means of conduits 103 and 104. The atomizer 102 and its associated conduits may be employed alone or in conjunction with the atomizer 97 and the pre-combustion chambers 95 and 96.

The details of the pre-combustion chamber are shown in Figs. 11 and 12. The main chamber of the pre-combustion chamber comprises a cylindrical outer or upper portion 105 and a frusto-conical inner or lower portion 106. A threaded tubular element 107 forms a continuation of the frusto-conical portion of the main chamber. The height H of the main chamber 105 is somewhat less than the internal diameter of the cylindrical portion. A conduit or passage 110 having a threaded, outwardly projecting end portion for connection with a conduit leading to the vaporizer or atomizer communicates with the interior of the main chamber in such a manner that fluid entering the main chamber is directed against a wall of the conical portion of the main chamber along a line normal thereto. The conduit 110 for introducing the vaporized or atomized fuel into the main chamber is surrounded by a water-cooling chamber 112 having threaded outlets 113 and 114 for connection to a water circulating system (not shown). A spark plug 115, connected to a high tension ignition system (not shown) of the type commonly employed on gasoline engines is mounted in a threaded opening in the end wall of the cylindrical portion of the main chamber with its spaced tips disposed adjacent the point at which the entering stream of atomized or vaporized fuel strikes the wall of the frusto-conical portion of the main chamber.

The details of the atomizers or vaporizers 97 and 102 are shown in Figs. 13 to 15. The main body of the atomizer is a metal block 116 having a centrally disposed cylindrical atomizing or vaporizing cavity or chamber 117 therein. Substantially parallel tangential inlet and outlet passages 120 and 121 communicating with the

interior of the cylindrical chamber are provided in opposite side portions of the block and on opposite sides of the axis of the cylindrical chamber. The outer portion of each passage is cylindrical and the inner portion is defined by two surfaces lying in parallel planes and two surfaces lying in planes diverging toward the cylindrical chamber. The width of the inner end of each passage is substantially equal to the length of the cylindrical chamber. Conduits 118 and 119, corresponding to the conduits 100 and 101 extending between the atomizer 97 and the pre-combustion chambers 95 and 96 or corresponding to the conduits 103 and 104 associated with the atomizer 102 of the apparatus illustrated diagrammatically in Fig. 7, are provided for conducting vaporizing or atomizing gas from a suitable source to the vaporizer or atomizer and for conducting the vaporized or atomized fuel from the vaporizer or atomizer to its points of use. The vaporizing or atomizing chamber 117 may be of any suitable size. I have obtained good results by employing chambers having internal diameters varying from about $\frac{1}{4}$ inch to about $\frac{1}{2}$ inch.

For introducing liquid fuel into the cylindrical chamber 117, a valve block 122 having relatively small inner and outer passages 123 and 124 communicating with a larger central cavity 125 is mounted in one side portion of the main body 116 with the inner passage 123 in axial alignment with the cylindrical chamber 117. The flow of fuel into the cylindrical chamber 117 through the inner passage 123 is controlled by means of a needle valve 126 suitably mounted for adjustable positioning axially in an opening in the opposite side portion of the main body. A ball 127, normally held in engagement with the inner peripheral edge of the outer passage 124 within the valve block cavity 125 by means of a spring 130, forms a check valve for preventing the back flow of gases from the cylindrical chamber 117 in the main body 116. A tube or conduit 131 communicates with the outer passage 124 and a source of supply of liquid fuel (not shown).

A duplex or double-chamber atomizer or vaporizer is shown in Figs. 16 and 17. The duplex atomizer comprises a main body 132 having oppositely disposed, axially aligned cylindrical atomizing or vaporizing chambers 133 and 134 there-in. The inner surfaces of the vaporizing chambers 133 and 134 are grooved circumferentially to facilitate picking up of the oil by the high velocity gas streams. Tangential inlet and outlet passages 135 and 136 having their axes forming a right angle communicate with the interior of the cylindrical vaporizing or atomizing chamber 134 through a common opening in the wall of the chamber. Conduits 137 and 140 communicate with the passages 135 and 136 and serve to conduct vaporizing or atomizing gas from a suitable source to the vaporizer or atomizer and to conduct the vaporized or atomized fuel from the vaporizer or atomizer to its points of use. Similar inlet and outlet passages are associated in a similar manner with the vaporizing or atomizing chamber 133, and conduits similar to the conduits 137 and 140 are associated with such passages.

Liquid fuel is introduced into both vaporizing or atomizing chambers 133 and 134 through a common passage 141 in the main body 132. The common passage communicates with passages 142 and 143 which are in axial alignment with the atomizing and vaporizing chambers 133 and 134. The fuel is introduced into the common

passage through a valve block 144, having relatively small inner and outer passages 145 and 146 communicating with a larger central cavity 147, mounted in one side portion of the main body 132.

The flow of liquid fuel into the vaporizing or atomizing chambers 133 and 134 through the axially aligned passages 142 and 143 is controlled by means of needle valves 150 and 151 suitably mounted for adjustable positioning axially in openings in the opposite side portions of the main body.

A ball 152 normally held in engagement with the inner peripheral edge of the outer passage 146 within the valve block cavity 147 by means of a spring 153 forms a check valve for preventing the back flow of gases from the vaporizing or atomizing chambers 133 and 134 through the common passage 141.

In the modified apparatus shown in Fig. 18, similar tubes 154 and 155 connect the atomizer 162 with the precombustion chambers 95 and 96, respectively, and are provided with check valves 156 and 157, respectively, located at or near their precombustion chamber ends. The check valves 156 and 157 permit fluid flow from the atomizer 162 through the tubes 154 or 155 to either precombustion chamber, but prevent flow in the opposite direction through either tube.

Similar tubes 158 and 159 connect the atomizer 162 with the main combustion chambers of cylinders 20 and 21, respectively, and are provided with check valves 159A and 160, respectively, located at or near their atomizer ends. These check valves serve to permit flow through either tube into the atomizer and prevent flow from the atomizer into either tube. Liquid fuel may be introduced into the atomizer chamber in any suitable manner, as, for example, through the axially arranged passage 168.

The atomizer 162, shown in detail in Fig. 19, provides tangential outlet passages 163 and 164 leading from the chamber 167 to the tubes 154 and 155, respectively. Other tangential inlet passages 165 and 166 communicate with the interior of the atomizing chamber and with the check valves 159A and 160, respectively, and through them with their respective tubes 158 and 159. The check valves 156 and 157, shown diagrammatically in Fig. 18, are similar to the check valves 159 and 160 which are shown in detail in Fig. 19, but are arranged to permit flow in the direction away from the atomizing chamber and not into it, whereas check valves 159 and 160 permit flow into the atomizing chamber and not away from it.

The mode of operation of the apparatus illustrated in the drawings will be clear from a consideration of the following description. When the crank shaft of the engine illustrated in Figs. 1 to 8, inclusive, is rotated in either direction, the pistons 25 and 26 will move away from each other, and the pistons 23 and 24 will move toward each other. The outer end of the piston 26 will close the ports 64, compress air in the outer end portion of the scavenging pump cylinder 30, and draw oil-laden atmosphere from the crank case through the passages 93 and 94 into the inner end portion of the scavenging pump cylinder. The piston 24 will close the exhaust ports 51 and 70, the piston 23 will close the transfer ports 55, so air will be compressed in the power cylinder 20, and a partial vacuum will be created in the outer end portion of the scavenging pump cylinder 21. Continued movement will close the 75

ports 63 and cause air to be forced from the inner end portion of the scavenging pump cylinder 27 through the passages 91 and 92 into the crank case. Upon further movement, the ports 63 will be opened into the outer end portion of the scavenging pump cylinder 27, relieving the vacuum therein, and the piston 25 will open the exhaust ports 52 just prior to the time when the piston 26 opens the transfer ports 56 and permits compressed air from the outer end portion of the scavenging pump cylinder 30 to flow to the interior of the power cylinder 21. Rotation of the crank shaft through the succeeding 180° will cause each of the operations just described to be repeated in the opposite cylinders.

It will be seen that if, during the compression stroke in either power cylinder (20 or 21) fuel should be injected by suitable means to form a combustible mixture, and if, at the proper time, this fuel charge should be ignited, combustion and expansion will take place and power will be developed.

It has been shown that during the operation of the engine, alternate suction and compression takes place in the inner end portions of the scavenging pump cylinders 27 and 30. This action causes atmosphere from the crank case to be carried back and forth through the passages 91, 92, 93 and 94. I provide forced feed lubrication to the crank shaft and crank pin bearings, by suitable conventional means which are not shown in the drawings. This forced feed lubrication produces, as is well known, a mist of lubricating oil in the crank case, and it is obvious that this mist will be carried, in the manner just explained, out to the inner end portions of the scavenging pump cylinders. Proper relationships should be established between the aggregate areas of the passages 91, 92, 93 and 94 and the volumes of air caused to pass through them during each stroke of the engine, so that the velocity through the passages will be high enough to support and transfer, at minimum engine speeds, a sufficiency of oil. It will be further observed that the oil thus carried, impinges against the inner end walls of the large-diameter portions of the step pistons 23 and 26 and is distributed by turbulence to lubricate all rubbing surfaces of said pistons without becoming mixed with the scavenging air which is being pumped by the opposite sides of said pistons.

Figs. 9 and 10 illustrate a modified arrangement of the engine in which the two pairs of crank pins have their axes in the same circle, but spaced more and/or less than 180° apart therein. With this arrangement, the engine will function properly when rotation is in one direction only. For the arrangement and crank positioning shown in Figs. 9 and 10, the correct direction of rotation is indicated by the arrow in Fig. 10. In the position of parts shown in Fig. 9, the piston 24 is seen to have completed its outward or power stroke and to have started on its compression stroke; whereas the piston 23, in the same cylinder, has just completed its outward or power stroke. In other words, the piston 24 is several degrees of crank shaft rotation in advance of the piston 23. Thus, the exhaust port 51 was opened by the piston 24 before the transfer port 55 was opened by the piston 23, and the exhaust port 51 has been closed by the piston 24 while the transfer port 55 is yet open. Therefore, compressed air from the outer end portion of the scavenging cylinder 27 will continue to flow into the power cylinder 20 after the exhaust port

51 is closed, and in this way the powder cylinder 20 can be filled with air under greater pressure at the beginning of the compression stroke therein, than is possible with a crank shaft having pairs of throws or pins 180° apart. Engine capacity may thus be increased with a sacrifice of perfect balance. 5

Following are some of the advantages permitted by engine designs embodying my invention:

(1) Perfect balance of all rotating and reciprocating parts. This is accomplished by making both groups of oppositely moving reciprocating elements equal to each other in weight, and by providing oppositely disposed and identically proportioned and weighted pairs of connecting rods, all of which always assume at the same time the same angle with respect to the axes of the cylinders; and by controlling one group of reciprocating parts by means of one of said pairs of connecting rods, and the other group of reciprocating parts by the other pair of connecting rods. Consequently, the accelerations of the two groups of reciprocating parts are always equal and opposite, producing inertia forces that have a zero resultant. Rotating and gyrating forces are also obviously balanced for the same reasons. 10

(2) Forces acting on the crank pin bearings due to either combustion, inertia or centrifugal pressures, act always as pure couples and thus do not produce radial loads on the main bearings. 30

(3) Forces acting on the crank pin and wrist pin bearings due to combustion in the power cylinder, are diminished during the first part of every power stroke by inertia of the reciprocating parts; and the loads on the same bearings due to inertia of the reciprocating parts are diminished during the latter part of every power stroke by compression pressure between the opposed pistons in the opposite cylinder. Thus, bearing loads are diminished and the turning effort is more uniform. 35

(4) Scavenging pump displacements are provided in excess of the combined displacement plus clearance space of the power cylinders they serve, which insures clean scavenging and full charges of air.

In the operation of engines of the type illustrated in the drawings with oil, employing atomizers of the type illustrated in Figs. 13, 14 and 15, the tangential passages 120 and 121 of 50 the atomizer or vaporizer may be operatively connected with the interiors of the power cylinders 20 and 21 by means of the conduits 118 and 119.

The oil is introduced into the vaporizing or atomizing chamber 117 under pressure through 55 the conduit 131 and the passages in the valve block 122. The oil entering the atomizer or vaporizer is atomized or vaporized by hot combustion gases flowing alternately from the power cylinders 20 and 21 through the conduits 118 and 60 119 (corresponding to conduits 100 and 101 or 103 and 104), and the resulting atomized or vaporized product flows alternately to the interiors of the power cylinders 20 and 21 or to the interiors of the cylinders 20 and 21 through the pre-combustion chambers 95 and 96. 65

During the course of a typical operation, oil of say 27° Bé. enters the atomizing or vaporizing chamber 117 which has become heated by the hot gases from the cylinders to a temperature 70 ranging upward of 300° F. (about 150° C.), and the viscosity is reduced to between 3° and 5° Engler (15 to 17 sec. Saybolt). This reduction in viscosity renders the oil much easier to atomize, probably because it reduces the surface tension. 75

The hot gases passing through the atomizer from one cylinder to the other, pick up the oil and revolve it at an extremely high velocity in the cylindrical chamber 117 from which it escapes 5 in a highly atomized state and is carried with the hot gases through the tube 118 or 119 into the combustion chamber of the engine.

The rapid revolution of the oil in the cylindrical chamber produces great pressure on the oil due 10 to centrifugal force, and this pressure tends to overcome the surface tension so that the oil can be blown off the edge or lip of the outlet port 120 or 121 of the atomizer in the form of drops so small that they appear as a mist or gas in 15 the atmosphere which floats upward and does not seem to come down. It appears that successful atomization is largely a matter of overcoming surface tension, and, to accomplish atomization, I use the heat of the gases from the combustion chamber of the engine to reduce the surface tension and the kinetic energy of the high-velocity gas-flow to produce pressure on the oil due to centrifugal force. The angular velocity 20 imparted to the oil gives it a tendency to pass 25 the outlet opening from the atomizing chamber without going out through the outlet, and a portion of the oil, at the beginning of the process, goes on around and around the chamber and is spread by centrifugal force on the inner surface 30 of the bore and reaches the outlet lip in a thin film, or perhaps a series of films moving at different velocities, and this film is broken up by the out-rushing gases into tiny particles as it leaves the lip of the outlet port. The tubes associated with the atomizer, as well as the atomizer body, become heated by the gases, so that 35 the oil is not only atomized but it is at least partially vaporized before it reaches the engine cylinder.

40 I prefer to control the temperature of the tubes associated with the atomizer, or keep it low enough to prevent pyrogenic decomposition of the fuel, or to avoid cracking it until after it reaches the combustion chamber. This avoids 45 the formation of carbon deposits in the tubes, and I have found that copper tubes are better for this purpose than tubes made of other materials. Without any special provision for cooling, copper tubes of a certain size and wall thickness 50 remain free from carbon, while identical tubes made of steel or brass become choked. The tubes get hottest at points near the combustion chambers, and I have found that it is desirable, when using tubes larger than $\frac{3}{2}$ " inside diameter, to provide additional radiating surface, 55 as by finning the tubes, for a portion of their length near their combustion chamber ends, and to insulate them to prevent heat transfer to the atmosphere for a portion of their length near the atomizer. This maintains more uniform temperatures 60 throughout the length of each tube and increases the temperature of the gases reaching the atomizer. It is also desirable to insulate the body of the atomizer, allowing only enough 65 heat to be radiated from the body to keep its temperature below the point at which free carbon will be liberated from the fuel and deposited in the atomizer or tubes.

When one cylinder is firing, the other is compressing. The gas pressure in the cylinder which is just beginning its power stroke is much greater than the pressure in the opposite cylinder, which is just beginning its compression stroke, thus hot gas flows through the tube and atomizer 75 and carries a charge of atomized fuel into the

cylinder which is compressing. As this stroke nears completion in each cylinder, the rising compression pressure in one cylinder will first equal and then exceed the falling combustion pressure in the opposite cylinder, and at this point the direction of flow through the tubes and atomizer will be reversed and this reverse flow will be accelerated by the rapid rise in pressure due to combustion in the cylinder which has just completed its compression stroke. Thus, 5 the cylinders alternate in charging each other with atomized fuel, the atomizer functioning identically with gas flow in either direction.

I have found that with compression ratios which are usual in gasoline engines, the compression pressure in one cylinder does not sufficiently exceed the gas pressure in the opposite cylinder to overcome the inertia of the gas in the tubes and cause a reverse flow of any appreciable volume of gas and fuel until after ignition takes place in 10 one cylinder and the exhaust and inlet ports open in the opposite cylinder. Even after the pressure differences in the two cylinders reach a maximum, which is approximately at the end of the stroke, with ports open in one cylinder and maximum 15 combustion pressure in the other, there is a lag, due to inertia and friction in the tubes and back pressure or resistance caused by centrifugal force and turbulence in the atomizer, so that no measurable amount of fuel ever enters a cylinder during 20 the time that the ports are open which would cause unburned fuel to be carried out the exhaust ports. I provide a safeguard against this possible waste of fuel which is particularly suitable for use in the operation of engines which must 25 operate for considerable periods of time at very low speed. For such conditions I preferably provide two atomizers and two sets of tubes (as illustrated in Figs. 7 and 9), one set carrying fuel to pre-combustion chambers and one set carrying 30 fuel to the main cylinders of the engine. I position the tubes of the latter set so that they penetrate the cylinder walls at points which are covered by the pistons in each cylinder during the time that the ports are open in the opposite cylinder, and thus no fuel can be injected directly 35 into a cylinder during the time that its ports are open. I find that fuel injected into pre-combustion chambers is never carried out through the 40 exhaust ports.

Fuel may be supplied to the atomizer under constant pressure, which need not exceed one-tenth of the maximum pressure resulting from combustion in the cylinders, or it may be supplied by a displacement pump, or metering pump, 55 which forces into the atomizer chamber a measured quantity of fuel oil during the compression stroke of each opposite cylinder. Constant pressure fuel supply is preferable because a very simple and cheap pump, such as a gear pump, may be 60 used. However, a metering pump of any suitable or well known construction can be used to supply individual atomizers of a plurality of pairs of cylinders with approximately equal quantities of fuel 65 per cycle per cylinder; and, it is to be noted, such pumps will function with more nearly identical equal volumes of discharge per cylinder, when operating in connection with this low-pressure system, than they do when used for injecting 70 under pressures of from 2000 to 9000 lbs. per square inch, as is done in Diesel type engines.

Instead of employing two-way atomizers, it is possible to employ one-way atomizers, cross connected by tubes to the pre-combustion chambers 75

and/or the cylinders. In this case, however, it will be necessary to employ check valves, to limit flow of gas through each atomizing device to one direction. The duplex atomizer of Figs. 16 and 5 17 can also be used in place of the two atomizers 97 and 102.

A suitable fuel system including a one-way atomizer is shown in Figs. 18 and 19. When, in the operation of apparatus of the type shown in 10 Figs. 18 and 19, the pressure in the cylinder 21 exceeds the pressure in the cylinder 20, gas will flow through the tube 159, the atomizer 162 and the tube 154 into the pre-combustion chamber 95; and during this phase there will be no flow 15 through either of the other two tubes of the system. Then, when the pressure in cylinder 20 exceeds the pressure in cylinder 21, gas will flow through the tube 158, the atomizer 162 and the tube 155 into the pre-combustion chamber 96; 20 and during this phase, there will be no flow through either tube 154 or 160. Thus, I have provided two sets of tubes each of which carries 25 gases from the main combustion chamber of one cylinder of the engine through a common atomizing chamber to the pre-combustion chamber of the opposite cylinder, and this flow is in one direction only in each set of tubes.

I have found that a residuum of fuel will remain in the tubes 154 and 155 following the injection 30 period, and an object of the arrangement just described is to prevent this fuel from being directly exposed to the intensely hot gases of combustion until after such gases have been cooled sufficiently so that they will not effect 35 pyrogenic decomposition of the fuel and consequent deposition of carbon in the tubes. This adequate cooling of the gas products of combustion is accomplished by preventing fuel from entering either tube 158 or 159, and by conducting 40 the gases from the cylinders through these tubes to the atomizer before such gases can come into contact with any fuel. A considerable cooling of the gases takes place during passage through the tubes 158 or 159, due to heat dissipation through 45 the tube walls, and a further cooling is effected by expansion of the gases into the atomizing chamber. Remaining heat in the gases is employed in vaporizing and atomizing the fuel.

The provision of precombustion chambers in 50 the complete combination of my invention permits the use of higher compression pressures acting upon combustible mixtures of fuel and air without causing pre-ignition and without causing detonation. In the operation of apparatus provided with pre-combustion chambers, the major 55 portion of the fuel is injected into the precombustion chambers by means of gases diverted from the cylinders of the engine. The gases which last enter either precombustion chamber 60 during the injection period are burned gases, being products of combustion in the opposite cylinder.

The precombustion chamber is so shaped and the flow of said gases which carry the fuel charge 65 into it is so directed that practically the entire fuel charge is retained within the pre-combustion chamber during the entire compression stroke. At the beginning of the compression stroke, the pre-combustion chamber is entirely 70 filled, except for the atomized or vaporized fuel, with burned gases. Thus, there is no explosive or combustible mixture in the engine until the time when the rising compression pressure in the main cylinder has become high enough to force a sufficient 75 quantity of air into the pre-combustion

chamber with the burned gases to produce a combustible mixture therein.

In employing a pre-combustion chamber having the characteristics and proportions of that shown and described, in conjunction with the engine of my invention, I find that I can use 5 much higher compression pressures, without causing ignition due to the heat of compression, than would be possible in an engine which did not embody these features and which similarly had 10 fuel present in the combustion chamber during all or a major part of the compression stroke. This is true whether my engine is operated on gasoline or heavier oils, and it permits exact timing of ignition by means of a spark plug located 15 in the pre-combustion chamber, and brings about increased engine efficiency and capacity by permitting a higher compression ratio.

Detonation is caused by exceedingly rapid flame spread in a combustible mixture and by compression waves which travel through the mixture in advance of the flame sphere and bring the mixture adiabatically to the ignition temperature. I avoid detonation by using burned gases to shield 20 the fuel charge in a relatively small pre-combustion chamber so that, even though the compression temperature and pressure exceeds the usual detonation point for the fuel used, the mixture lacks sufficient air to permit ignition, except as the result of a spark, or to support rapid flame 25 propagation. The fuel ejected from the pre-combustion chamber into the main cylinder by means of the pressure generated by this incomplete combustion, will not cause detonation in the cylinder because the rate of flame spread in 30 the air charge of the cylinder can not exceed the velocity at which the fuel moves into that air. That is, the fuel must burn as it enters the air of the cylinder so that there is no combustible mixture ahead of the flame which could be caused 35 to detonate by the advancing compression waves. As a matter of fact, I find that with a certain pre-combustion chamber, and a compression pressure of 165 lb. ga., and using ordinary gasoline 40 as fuel, ignition can not be produced even with a spark until just about the end of the compression stroke; and no detonations occur. Increasing the compression pressure with this same pre-combustion chamber will cause a sufficient amount 45 of air to enter the chamber at an earlier time in the compression stroke and will thus permit advancing the spark to produce earlier ignition.

These objects and characteristics of my pre-combustion chamber are realized in greater or less degree regardless of whether the entire fuel 55 charge is introduced into the pre-combustion chamber, or entirely into the main cylinder, or partly into both, provided the spark plug is located in the pre-combustion chamber, because in any of these cases only a small amount of fuel 60 is burned in the pre-combustion chamber and it serves to provide a pilot flame causing a more uniform rate of flame spread in the main charge. A still further advantage of my pre-combustion chamber is that it protects the spark plug. It 65 is a fact well known to experimenters that the burning of heavy oil in an engine using spark ignition usually results in spark plug trouble. The character of this trouble varies from fouling with oil or soft carbon to coking with hard carbon and 70 to burning out of the plugs, and one or all of these difficulties appears when heavy oil is burned in ordinary engines with ordinary placement or positioning of the spark plug. One reason for this is imperfect atomization and distribution 75

of the fuel charge, but even with my atomizing and vaporizing system, which seemingly produces complete and perfect burning of the fuel, the trouble still persists unless the spark plug is 5 shielded from the main combustion space, and I have found that placing the plug in a small chamber separated from the main combustion space, and communicating therewith by means of a constricted passage, eliminates the difficulty. 10 A further feature of advantage in my fuel burning system, considered as a whole, in a preferred embodiment, including a two cylinder, two cycle, engine, with cylinders firing at different times, equipped with my atomizing and vaporizing 15 apparatus, and arranged to inject a portion of the fuel into the pre-combustion chambers, and a portion into the main cylinders, is that I can thereby cause a two-cycle engine to operate smoothly, with constant spark setting, and without 20 missing or detonating, throughout wide ranges of variations in speed and load. Smooth operation under idling or light-load conditions is accomplished in my engine by isolating a small fuel charge in a precombustion chamber with sufficient air to support its combustion. Thus I can 25 burn the small amount of fuel required for idling operation, whereas, if this small fuel charge was distributed throughout the entire air charge, as in ordinary gasoline two-cycle engines, either the 30 mixture would be too lean to be ignited, or the air charge would be restricted or reduced to such an extent that scavenging would be incomplete. With engines depending upon a hot surface for 35 igniting the fuel, the difficulty encountered is to maintain a sufficiently hot surface when the engine is burning a small amount of fuel, and to avoid over-heating the surface when the engine is operating at full load and speed.

When the engine is cold it should be started on 40 a light hydro-carbon fraction, such as gasoline, in place of Diesel oil. Thus in practice, the oil line connected to atomizer 131 can lead to a two-way valve, so that it can be placed in communication with either a supply of gasoline under 45 pressure, or a supply of Diesel oil. After the engine has been started in operation this valve is turned to supply Diesel oil.

While my fuel system has been specifically 50 shown and described in its application to two-cylinder two-cycle engines, it is obviously applicable to other engines. Thus, in a multiple-cylinder four-cycle engine, it is possible to provide tubes for conducting gases from the combustion chamber of each cylinder to a common atomizer, 55 a check valve being provided in each tube, preferably near its atomizer end, which prevents flow in the opposite direction. Another tube may communicate with the atomizer and with the interior of a manifold which conducts the air to 60 all of the cylinders of the engine for supporting combustion. By these means regulatable quantities of fuel vapor and atomized fuel may be injected into the air stream in the manifold each time combustion takes place in any cylinder of the engine.

If my fuel system be applied to a conventional 65 multiple-cylinder four-cycle engine, and if the fuel—partly vaporized and partly atomized—be sprayed into the inlet air stream in the manifold, it is then essential, or most desirable, if not 70 essential, that the air stream in the manifold shall move at high velocity. If the velocity falls below about 50 ft. per second, the vaporized portion of the fuel charge will more rapidly, or in 75 greater quantity, condense on the walls of the

manifold, and the atomized portions of the charge will tend to coalesce, producing larger fuel globules and less opportunity for the fuel to contact and combine with the atoms of oxygen in the air charge. Thus, it is desirable that the conduit through which air is supplied to the cylinders be restricted only sufficiently to maintain a minimum velocity of about 50 ft. per sec. and, preferably, a mean velocity of approximately 125 ft. per sec. at maximum power. It follows 10 that the usual practice in gasoline engines of throttling the air supply which, of course, reduces its velocity through the manifold, should not be resorted to under this system in order to operate the engine at low speed and low power output. If, on the other hand, a sufficient amount of fuel is introduced to the air stream of an ordinary gasoline engine to operate the engine at idling speed and no power output, and if the weight of air per cycle per cylinder is not 15 especially restricted, then the ratio of air to fuel will not be in such proportion as to produce a combustible mixture—too lean—and the charge will not be ignited by the spark. By my system, I provide an air supply to all cylinders with the 20 least possible restriction consistent with maintaining a velocity of not less than about 50 ft. per sec. at idling speed, and I then provide a precombustion chamber communicating with the interior of the cylinder through a restricted passage, 25 and ignition means associated with the precombustion chamber. I have found that by these means an air-fuel ratio, which would be too 30 lean in fuel to be ignitable in an ordinary gasoline engine combustion chamber, can be ignited and completely burned if the said precombustion chamber is employed. The reason for this is that the precombustion chamber—such as described herein—is not scavenged and remains, during the 35 exhaust phase of the cycle, filled with products of combustion, and thus, at the end of the compression stroke, the ratio of air to fuel within the precombustion chamber is in a proportion of less air to more fuel—because a portion of the space is occupied by inert gases—than that which obtains, or would obtain, within the main cylinder or main combustion space of a similar engine 40 operating without the precombustion chamber. Thus a mixture of air and fuel, with the fuel proportion too small to form an ignitable mixture 45 will, when compressed and partly driven into a precombustion chamber previously occupied by burned gases, form within the said precombustion chamber a mixture which can be ignited by the ignition means within said precombustion chamber.

I claim:

1. Apparatus of the class described comprising a crank shaft, spaced, axially aligned cylinders disposed on opposite sides of the crank shaft, two pistons mounted for reciprocating movement within the opposite end portions of each cylinder, means rigidly connecting the inner pistons and the outer pistons to form inner and outer piston units, and one or more connecting rods pivotally attached to each piston unit and to two or more crank pins of the crank shaft.

2. Apparatus of the class described comprising a crank shaft, spaced, axially aligned cylinders disposed on opposite sides of the crank shaft, two pistons mounted for reciprocating movement in opposite directions within the opposite end portions of each cylinder, means rigidly connecting the inner pistons and the outer pistons to form inner and outer piston units, and one or more

connecting rods pivotally attached to each piston unit and to two or more crank pins of the crank shaft.

3. The combination with a power unit comprising spaced, axially aligned cylinders and two piston units mounted for reciprocating movement within said cylinders, of a four-throw crank shaft disposed between said cylinders, and means for operatively connecting two crank pins with each piston unit.

4. Apparatus of the class described comprising spaced, axially aligned cylinders, two pistons mounted within the opposite end portions of each cylinder, means separately connecting the pistons mounted within the adjacent end portions of the cylinders and the pistons mounted within the opposite end portions of the cylinders to provide two reciprocable units, a four-throw crank shaft disposed between the cylinders, and means for connecting two crank pins with each reciprocable unit.

5. Apparatus of the class described comprising a crank shaft, a pair of spaced, axially aligned cylinders, pistons mounted within the adjacent end portions of said cylinders, step pistons mounted within the opposite end portions of said cylinders, and means separately connecting the pistons mounted within the adjacent end portions of the cylinders and the step pistons to provide two reciprocable units, said means connecting the pistons mounted in adjacent end portions of the cylinders comprising at least two straight-line elements spaced apart a distance not substantially exceeding the throw of the crank shaft.

6. Apparatus of the class described comprising a crank shaft, a crank case surrounding the crank shaft, a power cylinder disposed adjacent the crank shaft with its longitudinal axis normal to the axis of the crank shaft, interior of said power cylinder being isolated during normal operation from communication with the interior of the crank case, a step piston mounted within the portion of the power cylinder remote from the crank shaft with its large-diameter portion disposed outwardly, means connecting the piston with a crank pin on the crank shaft, an enlarged cylinder surrounding the large-diameter portion of the step piston and attached to and communicating with the power cylinder, and one or more passages communicating with the interior of the crank case and the interior of the cylinder surrounding the large-diameter portion of the step piston adjacent its point of attachment to the power cylinder.

7. Apparatus of the class described comprising a crank shaft, a crank case surrounding the crank shaft, a power cylinder associated with the crank case, interior of said power cylinder being isolated during normal operation from communication with the interior of the crank case, a piston mounted within the portion of the power cylinder adjacent the crank case, a step piston mounted within the opposite end portion of the power cylinder with its large-diameter portion disposed outwardly, means separately connecting each piston with a crank pin on the crank shaft, an enlarged cylinder surrounding the large-diameter portion of the step piston and attached to and communicating with the power cylinder, and one or more passages communicating with the interior of the crank case and the interior of the cylinder surrounding the large-diameter portion of the step piston adjacent its point of attachment to the power cylinder.

8. Apparatus of the class described comprising

a crank shaft, a crank case surrounding the crank shaft, spaced, axially aligned power cylinders associated with the crank case, interior of said power cylinder being isolated during normal operation from communication with the interior of the crank case, a piston mounted within the end portion of each power cylinder adjacent the crank case, a step piston mounted within the opposite end portion of each power cylinder with its large-diameter portion disposed outwardly, means connecting the pistons with crank pins on the crank shaft, enlarged cylinders surrounding the large-diameter portions of the step pistons and attached to and communicating with the power cylinders, and one or more passages communicating with the interior of the crank case and the interior of the cylinder surrounding the large-diameter portion of each step piston adjacent its point of attachment to the power cylinder with which it is associated.

9. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, one or more connecting rods pivotally attached to each piston unit and to two or more crank pins on the crank shaft, enlarged cylinders surrounding the large-diameter portions of the step pistons and attached to and communicating with the power cylinders, and one or more passages communicating with the interior of the crank case and the interior of the cylinder surrounding the large-diameter portion of each step piston adjacent its point of attachment to the power cylinder with which it is associated.

10. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, enlarged cylinders surrounding the large-diameter portions of the step pistons and attached to and communicating with the power cylinders, and one or more passages communicating with the interior of the crank case and the interior of the cylinder surrounding the large-diameter portion of each step piston adjacent its point of attachment to the power cylinder with which it is associated.

11. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting the pistons with crank pins on the crank shaft, scavenging pump cylinders surrounding the large-diameter portions of the step pistons attached to the power

cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, and one or more passages communicating with the outer end portion of each scavenging pump cylinder and with the interior of the adjacent power cylinder.

12. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, one or more connecting rods pivotally attached to each piston unit and to two or more crank pins on the crank shaft, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, and one or more passages communicating with the outer end portion of each scavenging pump cylinder and with the interior of the adjacent power cylinder.

Index.
13. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, and one or more passages communicating with the outer end portion of each scavenging pump cylinder and with the interior of the adjacent power cylinder.

65 14. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting the pistons with crank pins on the crank shaft, 70 enlarged cylinders surrounding the large-diameter 75

ter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, and means for delivering fuel to each power cylinder including a pre-combustion chamber having a restricted inlet passage communicating with the interior of the power cylinder and having ignition means associated therewith. 5 10

15. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, one or more connecting rods pivotally attached to each piston unit and to two or more crank pins on the crank shaft, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, and means for delivering fuel to each power cylinder including a pre-combustion chamber having a restricted inlet passage communicating with the interior of the power cylinder and having ignition means associated therewith. 15 20 25 30 35 40

16. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, and means for delivering fuel to each power cylinder including a precombustion chamber having a restricted inlet passage communicating with the interior of the power cylinder and having ignition means associated therewith.

17. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting the pistons 70 and the step pistons, and a flywheel 75.

with crank pins on the crank shaft, scavenging pump cylinders surrounding the large-diameter portions of the step pistons attached to the power cylinders and communicating with the power cylinders and with the atmosphere, one or more 5 passages communicating with the interior of the crank case and the interior of the scavenging pump cylinder surrounding the large-diameter portion of each step piston adjacent its point of 10 attachment to the power cylinder with which it is associated, one or more passages communicating with the outer end portion of each scavenging pump cylinder and with the interior of the adjacent power cylinder, and means for delivering 15 fuel to each power cylinder including a pre-combustion chamber having a restricted inlet passage communicating with the interior of the power cylinder and having ignition means associated therewith.

20. Apparatus of the class described comprising a crank shaft, a crank case surrounding the crank shaft, spaced, axially aligned power cylinders communicating with the crank case, a piston mounted within the end portion of each power 25 cylinder adjacent the crank case, a step piston mounted within the opposite end portion of each power cylinder with its large-diameter portion disposed outwardly; means rigidly connecting the inner pistons and the step pistons to form inner 30 and outer piston units, one or more connecting rods pivotally attached to each piston unit and to two or more crank pins on the crank shaft, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, one or more 35 passages communicating with the outer end portion of each scavenging pump cylinder and with the interior of the adjacent power cylinder, and means for delivering fuel to each power cylinder including a precombustion chamber having a restricted inlet passage communicating with the interior of the power cylinder and having ignition 40 means associated therewith.

19. Apparatus of the class described comprising a four-throw crank shaft, a crank case surrounding the crank shaft, spaced, axially aligned power cylinders communicating with the crank 55 case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, scavenging pump cylinders surrounding the large-60 diameter portions of the step pistons attached to the power cylinders and communicating with the power cylinders and with the atmosphere, one or more passages communicating with the interior of the crank case and the interior of the scaveng-65 ing pump cylinder surrounding the large-diameter portion of each step piston adjacent its point of attachment to the power cylinder with which it is associated, one or more passages communicating with the outer end portion of each scavenging pump cylinder and with the interior 70

of the adjacent power cylinder, and means for delivering fuel to each power cylinder including a pre-combustion chamber having a restricted inlet passage communicating with the interior of the power cylinder and having ignition means 5 associated therewith.

20. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting 10 the pistons with crank pins on the crank shaft, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, and means for delivering fuel to 15 each power cylinder including a source of supply of liquid fuel, a cylindrical atomizing chamber provided with tangentially arranged inlet and outlet passages, conduits connecting the tangential inlet and outlet passages with the interiors of 20 the power cylinders, and a conduit for introducing liquid fuel from the source of supply axially into the cylindrical atomizing chamber.

21. Apparatus of the class described comprising a crank shaft, a crank case surrounding the 35 crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, one or more connecting rods pivotally attached to each piston unit and to two or more crank pins on the crank shaft, enlarged cylinders surrounding the large-diameter portions of the step pistons and attached to and communicating with the power cylinders, one or more 40 passages communicating with the interior of the crank case and the interior of the cylinder surrounding the large-diameter portion of each step piston adjacent its point of attachment to the power cylinder with which it is associated, and means for delivering fuel to each power cylinder including a source of supply of liquid fuel, a cylindrical atomizing chamber provided with tangentially arranged inlet and outlet passages, conduits connecting the tangential inlet and outlet 45 passages with the interiors of the power cylinders, and a conduit for introducing liquid fuel from the source of supply axially into the cylindrical atomizing chamber.

22. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the 50 crank shaft with each piston unit, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, one or more passages communicating with the outer end portion of each scavenging pump cylinder and with the interior 55

of the adjacent power cylinder, and means for delivering fuel to each power cylinder including a pre-combustion chamber having a restricted inlet passage communicating with the interior of the power cylinder and having ignition means 60 associated therewith.

crank shaft with each piston unit, enlarged cylinders surrounding the large-diameter portions of the step pistons and attached to and communicating with the power cylinders, one or more 5 passages communicating with the interior of the crank case and the interior of the cylinder surrounding the large-diameter portion of each step piston adjacent its point of attachment to the power cylinder with which it is associated, and 10 means for delivering fuel to each power cylinder including a source of supply of liquid fuel, a cylindrical atomizing chamber provided with tangentially arranged inlet and outlet passages, conduits connecting the tangential inlet and outlet 15 passages with the interiors of the power cylinders, and a conduit for introducing liquid fuel from the source of supply axially into the cylindrical atomizing chamber.

23. Apparatus of the class described comprising a crank shaft, a crank case surrounding the crank shaft, spaced, axially aligned power cylinders communicating with the crank case, a piston mounted within the end portion of each power cylinder adjacent the crank case, a step piston 25 mounted within the opposite end portion of each power cylinder with its large-diameter portion disposed outwardly, means connecting the pistons with crank pins on the crank shaft, scavenging pump cylinders surrounding the large-diameter 30 portions of the step pistons attached to the power cylinders and communicating with the power cylinders and with the atmosphere, one or more passages communicating with the interior of the crank case and the interior of the scavenging pump cylinder surrounding the large-diameter 35 portion of each step piston adjacent its point of attachment to the power cylinder with which it is associated, one or more passages communicating with the outer end portion of each scavenging pump cylinder and with the interior of the adjacent power cylinder, and means for delivering fuel to each power cylinder including a source of supply of liquid fuel, a cylindrical atomizing chamber provided with tangentially arranged 40 inlet and outlet passages, conduits connecting the tangential inlet and outlet passages with the interiors of the power cylinders, and a conduit for introducing liquid fuel from the source of supply axially into the cylindrical atomizing chamber.

24. Apparatus of the class described comprising a crank shaft, a crank case surrounding the crank shaft, spaced axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting 50 the inner pistons and the step pistons to form inner and outer piston units, one or more connecting rods pivotally attached to each piston unit and to two or more crank pins on the crank shaft, scavenging pump cylinders surrounding the large-diameter 55 portions of the step pistons attached to the power cylinders and communicating with the power cylinders and with the atmosphere one or more passages communicating with the interior of the crank case and the interior 60 of the scavenging pump cylinder surrounding the large-diameter portion of each step piston adjacent its point of attachment to the power cylinder with which it is associated, one or more passages communicating with the interior of the crank case and the interior of the cylinder 65 surrounding the large-diameter portion of each step piston adjacent its point of attachment to the power cylinder with which it is associated, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet 70 passages, conduits connecting the tangential inlet and outlet passages of one atomizing chamber with the interiors of the pre-combustion chambers, conduits connecting the tangential inlet and outlet passages of the other atomizing chamber with the interiors of the 75

the interior of the adjacent power cylinder, and means for delivering fuel to each power cylinder including a source of supply of liquid fuel, a cylindrical atomizing chamber provided with tangentially arranged inlet and outlet passages, conduits connecting the tangential inlet and outlet passages with the interiors of the power cylinders, and a conduit for introducing liquid fuel from the source of supply axially into the cylindrical atomizing chamber.

25. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, one or more passages communicating with the outer end portion of each scavenging pump cylinder and with the interior of the adjacent power cylinder, and means for delivering fuel to each power cylinder including a source of supply of liquid fuel, a cylindrical atomizing chamber provided with tangentially arranged inlet and outlet passages, conduits connecting the tangential inlet and outlet passages with the interiors of the power cylinders, and a conduit for introducing liquid fuel from the source of supply axially into the cylindrical atomizing chamber.

26. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting the pistons with crank pins on the crank shaft, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet passages, conduits connecting the tangential inlet and outlet passages of one atomizing chamber with the interiors of the pre-combustion chambers, conduits connecting the tangential inlet and outlet passages of the other atomizing chamber with the interiors of the

power cylinders, and means for introducing liquid fuel from the source of supply axially into the cylindrical atomizing chambers.

27. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, one or more connecting rods pivotally attached to each piston unit and to two or more crank pins on the crank shaft, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet passages, conduits connecting the tangential inlet and outlet passages of one atomizing chamber with the interiors of the pre-combustion chambers, conduits connecting the tangential inlet and outlet passages of the other atomizing chamber with the interiors of the power cylinders, and means for introducing liquid fuel from the source of supply axially into the cylindrical atomizing chambers.

28. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet passages, conduits connecting the tangential inlet and outlet passages of one atomizing chamber with the interiors of the pre-combustion chambers, conduits connecting the tangential inlet and outlet passages of the other atomizing chamber with the interiors of the power cylinders, and means for introducing liquid fuel from the source of supply axially into the cylindrical atomizing chambers.

uid fuel from the source of supply axially into the cylindrical atomizing chambers.

29. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting the pistons with crank pins on the crank shaft, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, one or more passages communicating with the outer end portion of each scavenging pump cylinder and with the interior of the adjacent power cylinder, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet passages, conduits connecting the tangential inlet and outlet passages of one atomizing chamber with the interiors of the pre-combustion chambers, conduits connecting the tangential inlet and outlet passages of the other atomizing chamber with the interiors of the power cylinders, and means for introducing liquid fuel from the source of supply axially into the cylindrical atomizing chambers.

30. Apparatus of the class described comprising a crank shaft, a crank case surrounding the crank shaft, spaced axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, one or more connecting rods pivotally attached to each piston unit and to two or more crank pins on the crank shaft, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, one or more passages communicating with the outer end portion of each scavenging pump cylinder and with the interior of the adjacent power cylinder, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet passages, conduits connecting the tangential inlet and outlet passages of one atomizing chamber with the interiors of the pre-combustion chambers, conduits connecting the tangential inlet and outlet passages of the other atomizing chamber with the interiors of the power cylinders, and means for introducing liquid fuel from the source of supply axially into the cylindrical atomizing chambers.

chambers, conduits connecting the tangential inlet and outlet passages of the other atomizing chamber with the interiors of the power cylinders, and means for introducing liquid fuel from the source of supply axially into the cylindrical atomizing chambers.

31. Apparatus of the class described comprising a four-throw crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means rigidly connecting the inner pistons and the step pistons to form inner and outer piston units, means operatively connecting two crank pins on the crank shaft with each piston unit, scavenging pump cylinders surrounding the large-diameter portions of the step pistons attached to the power cylinders and communicating with the power cylinders and with the atmosphere, one or more passages communicating with the interior of the crank case and the interior of the scavenging pump cylinder surrounding the large-diameter portion of each step piston adjacent its point of attachment to the power cylinder with which it is associated, one or more passages communicating with the outer end portion of each scavenging pump cylinder and with the interior of the adjacent power cylinder, a pre-combustion chamber communicating with the interior of each power cylinder through a restricted passage, ignition means associated with each pre-combustion chamber, source of supply of liquid fuel, two cylindrical atomizing chambers provided with tangentially arranged inlet and outlet passages, conduits connecting the tangential inlet and outlet passages of one atomizing chamber with the interiors of the pre-combustion chambers, conduits connecting the tangential inlet and outlet passages of the other atomizing chamber with the interiors of the power cylinders, and means for introducing liquid fuel from the source of supply axially into the cylindrical atomizing chambers.

32. An atomizing device for liquid fuels comprising a cylindrical atomizing chamber having a circumferentially grooved inner surface and provided with tangentially arranged inlet and outlet passages.

33. An atomizing device for liquid fuels comprising a cylindrical atomizing chamber having a circumferentially grooved inner surface and provided with tangentially arranged inlet and outlet passages, and means for introducing liquid fuel axially into the atomizing chamber.

34. An atomizing device for liquid fuels comprising a cylindrical atomizing chamber provided with angularly arranged tangential inlet and outlet passages communicating with the interior of the chamber through a common opening in a wall thereof.

35. An atomizing device for liquid fuels comprising a cylindrical atomizing chamber provided with angularly arranged tangential inlet and outlet passages communicating with the interior of the chamber through a common opening in a wall thereof, and means for introducing liquid fuel axially into the atomizing chamber.

36. In the operation of an engine provided with a crank shaft, a crank case, a power cylinder, a step piston mounted for reciprocating movement within the portion of the power cylinder remote from the crank shaft and operatively

connected to a crank pin on the crank shaft, and a scavenging pump cylinder surrounding the large diameter portion of the step piston and provided with an air outlet port in one end portion thereof, the improvement which comprises circulating high velocity currents of oil-laden crank case atmosphere between the crank case and the end portion of the scavenging pump cylinder opposite the end portion in which the air outlet port is located, thereby to lubricate the rubbing surfaces of the step piston without mixing the lubricating oil with the scavenging air.

37. The combination with a multiple cylinder internal combustion engine of a pre-combustion chamber communicating with the interior of a cylinder through a restricted passage, ignition means associated with the pre-combustion chamber, a source of fuel, and conduits connecting the source of fuel with the pre-combustion chamber and with another cylinder to permit the use of combustion gases from said cylinder for injecting fuel directly into the pre-combustion chamber.

38. The combination with a two cylinder internal combustion engine of a pre-combustion chamber associated with each cylinder and communicating with the interior thereof through a restricted passage, ignition means associated with each pre-combustion chamber, a source of fuel, and a conduit connecting the source of fuel with each pre-combustion chamber to permit the use of combustion gases from each cylinder for injecting fuel directly into the pre-combustion chamber associated with the other cylinder.

39. The combination with a two cylinder internal combustion engine of a pre-combustion chamber associated with each cylinder and communicating with the interior thereof through a restricted passage, ignition means associated with each pre-combustion chamber, a source of liquid fuel, an atomizer, means connecting the source of liquid fuel with the atomizer, and a conduit connecting the atomizer with each pre-combustion chamber to permit the use of combustion gases from each cylinder for atomizing the liquid fuel and injecting the atomized fuel directly into the pre-combustion chamber associated with the other cylinder.

40. The combination with a two cylinder internal combustion engine of a pre-combustion chamber associated with each cylinder and communicating with the interior thereof through a restricted passage, ignition means associated with each pre-combustion chamber, a source of liquid fuel, a cylindrical atomizing chamber provided with tangentially arranged inlet and outlet passages, means connecting the source of liquid fuel with the atomizing chamber, and a conduit connecting a tangential passage with each pre-combustion chamber to permit the use of combustion gases from each cylinder for atomizing the liquid fuel and injecting the atomized fuel into the pre-combustion chamber associated with the other cylinder.

41. The combination with a two cylinder internal combustion engine of a pre-combustion chamber associated with each cylinder and communicating with the interior thereof through a restricted passage, ignition means associated with each pre-combustion chamber, a cylindrical atomizing chamber provided with tangentially arranged inlet and outlet passages, means for introducing liquid fuel axially into the atomizing chamber, and a conduit connecting a tangential passage with each pre-combustion chamber to

permit the use of combustion gases from each cylinder for atomizing the liquid fuel and injecting the atomized fuel into the pre-combustion chamber associated with the other cylinder.

42. The combination with a two cylinder internal combustion engine of an atomizer having tangential inlet and outlet passages, a source of supply of liquid fuel, means connecting the atomizer with the source of liquid fuel, and a conduit connecting the atomizer with the interior of each cylinder to permit the use of combustion gases from each cylinder for atomizing the liquid fuel and injecting the atomized fuel into the other cylinder.

43. The method of supplying fuel to the cylinders of a multiple cylinder internal combustion engine which comprises injecting a portion of the fuel directly into each cylinder and a portion into a pre-combustion chamber associated with said cylinder and communicating therewith through a restricted passage by means of combustion gases from another cylinder.

44. The method of operating a two cylinder, two-cycle, internal combustion engine which comprises introducing a portion of the combustible mixture into a pre-combustion chamber communicating with each cylinder through a restricted passage, introducing another portion of the combustible mixture directly into each cylinder, and igniting the combustible mixture in the pre-combustion chambers.

45. The method of operating a two cylinder, two-cycle, internal combustion engine which comprises introducing a major portion of the combustible mixture into a pre-combustion chamber communicating with each cylinder through a restricted passage, introducing the balance of the combustible mixture directly into each cylinder and igniting the combustible mixture in the pre-combustion chambers.

46. Apparatus of the class described comprising a crank shaft, a crank case surrounding the crank shaft, spaced, axially aligned power cylinders communicating with the crank case, a piston mounted within the end portion of each power cylinder adjacent the crank case, a step piston mounted within the opposite end portion of each power cylinder with its large-diameter portion disposed outwardly, means connecting the pistons with crank pins on the crank shaft, enlarged cylinders surrounding the large-diameter portions of the step pistons and attached to and communicating with the power cylinders, one or more passages communicating with the interior of the crank case and the interior of the cylinder surrounding the large-diameter portion of each step piston adjacent its point of attachment to the power cylinder with which it is associated, and means for delivering fuel to each power cylinder including a source of supply of liquid fuel, an atomizing chamber provided with inlet and outlet passages, conduits connecting the inlet and outlet passages with the interiors of the power cylinders, and a conduit for introducing liquid fuel from the source of supply into the atomizing chamber.

47. The combination with a two cylinder internal combustion engine of an atomizer, a source of supply of liquid fuel, means connecting the atomizer with the source of liquid fuel, an inlet conduit connecting the atomizer with the interior of each cylinder, an outlet conduit connecting the atomizer with the interior of each cylinder, means associated with the inlet conduits for preventing fluid flow from the atomizer to the cylinders,

and means associated with the outlet conduits for preventing fluid flow from the cylinders to the atomizer.

48. The method of operating a multiple cylinder internal combustion engine which comprises passing gases from the combustion chambers in contact with liquid fuel to vaporize or atomize the liquid fuel, mixing the resulting vaporized or atomized fuel with air, introducing the air-fuel mixture into a pre-combustion chamber, providing for restricted communication between the interior of the pre-combustion chamber and the interior of the cylinder, and igniting the air-fuel mixture in the pre-combustion chambers.

49. Apparatus of the class described comprising a crank shaft, spaced, axially aligned cylinders, two pistons mounted for reciprocating movement in opposite directions within the opposite end portions of each cylinder, straight-line means rigidly connecting the inner pistons and the outer pistons to form inner and outer piston units, and one or more connecting rods pivotally attached to each piston unit and to two or more crank pins of the crank shaft.

50. Apparatus of the class described comprising a four-throw crank shaft, spaced, axially aligned cylinders, two pistons mounted for reciprocating movement in opposite directions within the opposite end portions of each cylinder, means rigidly connecting the inner pistons and the outer pistons to form inner and outer piston units, and two connecting rods pivotally attached to each piston unit and to two crank pins of the crank shaft, the means rigidly connecting the inner pistons comprising two straight-line elements spaced apart a distance less than the diameter of the circle which defines the travel of the outermost points of the connecting rod ends which are journaled on the crank pins of the crank shaft, and space being provided between the two inner or adjacent crank pins for the free passage of said straight-line means connecting the inner pistons.

51. Apparatus of the class described comprising a crank shaft, axially aligned cylinders disposed upon opposite sides of the crank shaft, step pistons mounted for reciprocating motion within the cylinders and having their ends of large diameter disposed remote from the crank shaft, rigid straight line means connecting the step pistons to provide a single piston unit, and means for connecting the piston unit with a crank pin on the crank shaft.

52. Apparatus of the class described comprising a crank shaft having four crank pins, a crank case surrounding the crank shaft, two stationary power cylinders disposed in axial alignment on opposite sides of the crank shaft, an inner piston mounted within the end bore of each power cylinder adjacent the crank case, means comprising two straight columns disposed on opposite sides of the crank shaft and rigidly connecting the inner pistons in each power cylinder, said columns being spaced apart a distance less than the outside diameter of either of said inner pistons, a wrist pin carried by one of said inner pistons, two connecting rods pivotally attached to said wrist pin and to two crank pins of the crank shaft, an annular cross head disposed on the opposite side of the crank-shaft from the inner piston which carries a wrist pin and mounted to reciprocate in a bore adjacent the crank case and concentric with the axis of the power cylinders, two connecting rods pivotally attached to said cross head and to two crank pins of the

crank shaft, an outer piston mounted within the end bore of each power cylinder remote from the crank case, and means external to the power cylinders rigidly connecting the outer pistons and the cross head, all of said connecting rods being of identical length between the centers of their respective end bearings.

53. Apparatus of the class described comprising two stationary power cylinders disposed in axial alignment on opposite sides of a crank shaft, an inner and an outer piston mounted in the bore of each power cylinder, straight-line means external to the cylinder bores rigidly connecting the outer pistons, and straight-line means rigidly connecting the inner pistons.

54. In an opposed piston engine the combination of a crank shaft having a plurality of crank pins, two stationary power cylinders disposed in axial alignment on opposite sides of the crank shaft, an inner piston and an outer piston mounted in the bore of each power cylinder, straight-line means external to the cylinder bores rigidly connecting the outer pistons and straight-line means rigidly connecting the inner pistons to form inner and outer piston units, a connecting rod pivotally connecting the inner piston unit and the crank shaft, and a substantially identical connecting rod pivotally connecting the outer piston unit and the crank shaft and disposed on the opposite side of the crank shaft from the first mentioned connecting rod.

55. A device for atomizing liquid fuel by means of gases flowing under pressure, comprising a cylindrical chamber, means for introducing liquid fuel into said chamber, means for admitting gases to the interior of said chamber from an external source of gas supply in a direction substantially tangential to the bore of said chamber, and means for withdrawing a mixture of atomized fuel and gas from said chamber in a direction substantially tangential to the bore thereof.

56. A device for atomizing liquid fuels by means of gases flowing under pressure and adapted for association with a cylinder of an internal combustion engine, comprising a cylindrical atomizing chamber, means for introducing liquid fuel into the atomizing chamber, means for regulating the admission of the liquid fuel to the atomizing chamber, means for admitting gases to the interior of the atomizing chamber from an external source of supply of gas in a direction substantially tangential to the bore of said chamber, and means for withdrawing a mixture of atomized fuel and gas from said chamber in a direction substantially tangential to the bore thereof.

57. A device for atomizing liquid fuels by means of gases flowing under pressure and adapted for association with a cylinder of an internal combustion engine, comprising a cylindrical atomizing chamber, means for introducing liquid fuel into the atomizing chamber, a needle valve for regulating the admission of the liquid fuel to the atomizing chamber, means for admitting gases to the interior of the atomizing chamber from an external source of supply of gas in a direction substantially tangential to the bore of said chamber, and means for withdrawing a mixture of atomized fuel and gas from said chamber in a direction substantially tangential to the bore thereof.

58. A device for atomizing liquid fuels by means of gases flowing under pressure and adapted for association with a cylinder of an internal combustion chamber, comprising a plurality of cylindrical atomizing chambers, means for introduc-

ing liquid fuel into each atomizing chamber, and means for admitting gases to the interior of each atomizing chamber from an external source of supply of gas in a direction substantially tangential to the bore of said chamber.

59. A device for atomizing liquid fuels by means of gases flowing under pressure and adapted for association with a cylinder of an internal combustion chamber, comprising a plurality of cylindrical atomizing chambers, means for introducing liquid fuel into each atomizing chamber, means for regulating the admission of liquid fuel to each atomizing chamber, and means for admitting gases to the interior of each atomizing chamber from an external source of supply of gas in a direction substantially tangential to the bore of said chamber.

60. A device for atomizing liquid fuels by means of gases flowing under pressure and adapted for association with a cylinder of an internal combustion engine, comprising a cylindrical atomizing chamber, a conduit through which liquid fuel may be introduced into the atomizing chamber, means associated with said conduit to prevent the flow of liquid fuel therethrough from the atomizing chamber, means for admitting gases to the interior of the atomizing chamber from an external source of supply of gas in a direction substantially tangential to the bore of said chamber, and means for withdrawing a mixture of atomized fuel and gas from said chamber in a direction substantially tangential to the bore thereof.

61. In the operation of an opposed piston engine provided with two stationary power cylinders disposed in axial alignment on opposite sides of a crank shaft, a piston mounted within the end portion of each power cylinder adjacent the crank shaft, a step piston mounted within the opposite end portion of each power cylinder with its large-diameter portion disposed outwardly with respect to the crank shaft, means rigidly connecting the inner pistons and the step pistons to form inner and outer piston units, means operatively connecting each piston unit with one or more crank pins of the crank shaft, and a scavenging pump cylinder surrounding the large diameter portion of each step piston and provided with an air outlet port in the outer end portion thereof, the improvement which comprises circulating high velocity currents of oil-laden crank case atmosphere between the crank case and the end portion of the scavenging pump cylinder opposite the end portion in which the air outlet port is located, thereby to lubricate the rubbing surfaces of the step piston without mixing the lubricating oil with the scavenging air.

62. The combination with a multiple cylinder internal combustion engine of a pre-combustion chamber associated with each cylinder and communicating with the interior thereof through a restricted passage, ignition means associated with each pre-combustion chamber, an atomizer, a source of supply of liquid fuel, means connecting the atomizer with the source of liquid fuel, an inlet conduit connecting the atomizer with the interior of each cylinder, an outlet conduit connecting the atomizer with the interior of each pre-combustion chamber, means associated with the inlet conduits for preventing fluid flow from the atomizer to the cylinders, and means associated with the outlet conduits for preventing fluid flow from the pre-combustion chambers to the atomizer.

63. The combination with a two cylinder internal combustion engine of a pre-combustion

chamber associated with each cylinder and communicating with the interior thereof through a restricted passage, ignition means associated with each pre-combustion chamber, a source of fuel, 5 conduits connecting the source of fuel with each pre-combustion chamber to permit the use of combustion gases from each cylinder for injecting fuel directly into the pre-combustion chamber associated with the other cylinder, and additional conduits connecting the source of fuel 10 directly with each cylinder to permit the use of combustion gases for injecting fuel directly into the other cylinder.

64. The method of operating an internal combustion engine which comprises atomizing and 15 incorporating liquid fuel in combustion gases from one cylinder of the engine, introducing the combustion gas-fuel mixture into a pre-combustion chamber associated with another cylinder 20 of the engine and communicating therewith through a restricted opening, introducing air into the pre-combustion chamber, and igniting the fuel therein.

65. Apparatus of the class described comprising 25 a crank shaft, axially aligned cylinders disposed on opposite sides of the crank shaft, two pairs of pistons of substantially equal weights mounted in the cylinders for reciprocating movement with one pair disposed in each cylinder, a 30 dynamically balanced, straight-line system of connecting rods of substantially equal lengths and weights for transmitting reciprocating movement of the pistons to the crank shaft, means for supplying the cylinders with a combustible mixture 35 of air and fuel, and means for igniting the combustible mixture at each 180 degrees of crank shaft rotation.

66. Apparatus of the class described comprising 40 a crank shaft, axially aligned cylinders disposed on opposite sides of the crank shaft, two pairs of pistons of substantially equal weights mounted in the cylinders for reciprocating movement with one pair disposed in each cylinder, a 45 dynamically balanced, straight-line system of connecting rods of substantially equal lengths and weights for transmitting reciprocating movement of the pistons to the crank shaft, means for supplying the cylinders with a combustible mixture 50 of air and fuel, and means for igniting the combustible mixture at each 180 degrees of crank shaft rotation, the weights of the oppositely disposed reciprocating masses being such that their combined inertias at normal operating speed shall balance the total compression pressure imposed upon the combustible mixture at the time 55 of ignition.

67. In combination with an internal combustion engine, a pre-combustion chamber associated with a power cylinder of the engine and 60 communicating with the interior thereof through a restricted passage, said pre-combustion chamber comprising a cylindrical body, a substantially flat end wall remote from the restricted passage, an opposite or inner end wall forming in cross 65 section a frustrated cone the inner surface of which converges from a base diameter equal to the inside diameter of said cylindrical body to a diameter equal to said restricted passage, ignition means associated with said pre-combustion 70 chamber, a spray nozzle or conduit, penetrating

the outer end wall of said pre-combustion chamber, for the purpose of conveying liquid fuel to said pre-combustion chamber, a source of fuel supply to said nozzle, said spray nozzle being so positioned and its spray angle so determined that fuel sprayed through it will impinge against the inner surface of said inner end wall, the length of the cylindrical portion of said pre-combustion chamber being less than its diameter. 5

68. Apparatus of the class described comprising 10 a crank shaft, axially aligned cylinders disposed upon opposite sides of the crank shaft, two pistons mounted for reciprocating movement within opposite end portions of each cylinder, means rigidly connecting inner and outer pistons 15 to form inner and outer piston units, and connecting rods connecting each piston unit to two crank pins of the crank shaft.

69. Apparatus of the class described comprising 20 a crank shaft, axially aligned cylinders disposed upon opposite sides of the crank shaft, two pistons mounted for reciprocating movement within opposite end portions of each cylinder, straight-line means connecting the inner and outer piston units, and connecting rods connecting 25 each piston unit to two crank pins of the crank shaft, the crank pins to which the inner piston unit is connected being spaced apart to accommodate the straight-line connecting means connecting the inner pair of pistons without interfering 30 with operation of the crank shaft.

70. The method of providing a combustible mixture of air and fuel for operating a multiple cylinder internal combustion engine which comprises introducing fuel into a substantially cylindrical atomizing chamber, introducing combustion gases from a cylinder of the engine tangentially into said chamber to produce a whirling current of gas and to form a mixture of atomized or vaporized fuel and combustion gas, 40 and introducing the resulting fuel-combustion gas mixture into a body of air in a cylinder of the engine. 45

71. The method of providing a combustible mixture of air and fuel for operating a multiple 50 cylinder internal combustion engine which comprises introducing fuel into a substantially cylindrical atomizing chamber, introducing combustion gases under pressure from a cylinder of the engine tangentially into said chamber to produce a whirling current of gas and to form a mixture of atomized or vaporized fuel and combustion gas, and introducing the resulting fuel-combustion 55 gas mixture into a body of air in a cylinder of the engine.

72. The method of operating an internal combustion engine which comprises introducing fuel into a substantially cylindrical atomizing chamber, introducing combustion gases from one cylinder of the engine tangentially into said chamber 60 to produce a whirling current of gas and form a mixture of atomized or vaporized fuel and combustion gases, introducing the resulting fuel-combustion gas mixture into a precombustion chamber communicating with the interior of another cylinder of the engine through a restricted opening, introducing air into the precombustion chamber, and igniting the fuel therein. 65
